UNITED STATES PATENT OFFICE

140,442

DESIGN FOR AN ELECTRIC BROILER HEATING UNIT

Morris A. Feinstein, Chicago, Ill.

Application October 20, 1944, Serial No. 115,886

Term of patent 14 years

(Cl. D81—26)

To all whom it may concern:

Be it known that I, Morris A. Feinstein, a citizen of the United States, residing at Chicago, in the county of Cook and State of Illinois, have invented a new, original, and ornamental Design for Electric Broiler Heating Units, of which the following is a specification, reference being had to the accompanying drawing, forming part thereof.

Fig. 1 is a top plan view of an electric broiler heating unit, showing my new design;

Fig. 2 is a front elevational view thereof with the terminal member omitted for convenience of illustration; and

Fig. 3 is a bottom plan view.

The dominant features of the design reside in the portions shown in full lines.

I claim:

The ornamental design for an electric broiler heating unit, as shown and described.

MORRIS A. FEINSTEIN.
